UNITED STATES PATENT OFFICE.

HENRY PODOLSKY, OF SAN FRANCISCO, CALIFORNIA.

STOVE.

1,370,150.

Specification of Letters Patent.

Patented Mar. 1, 1921.

Application filed July 28, 1919. Serial No. 313,834.

To all whom it may concern:

Be it known that I, HENRY PODOLSKY, a citizen of the United States, residing at San Francisco, in the county of San Francisco, State of California, have invented a new and useful Stove, of which the following is a specification in such full and clear terms as will enable those skilled in the art to construct and use the same.

10 This invention relates to a kitchen stove or range and its object is to provide means whereby the greatest possible amount of heat units may be abstracted from the fuel for the purpose of heating the oven.

15 This invention, while applicable to any range, is particularly useful in connection with oil burners where there is a blast which tends to draw most of the heat out of the chimney rather than deliver it to the flues of 20 the stove.

Other objects of the invention will appear as the description proceeds.

An embodiment of the invention is shown in the accompanying drawings in which the 25 same reference numeral is applied to the same portion throughout, but I am aware that there may be modifications thereof.

Figure 1 is a perspective view of the stove with portions broken away to show the interior construction of the flues,

30 Fig. 2 is a plan view of the stove with certain of the covers removed for purposes of illustration, and

Fig. 3 is an end elevation of the stove 35 with a portion broken away for the purpose of showing the flues.

In the drawings: the numeral 1 indicates the exterior stove casing, which has the oven 2, fire box 3, oven door 4, the ash door 40 5, the fire door 6, and damper 7, all of a well known construction. The top of the stove may be of any desired form and have any number of covers 8 desired.

The flues of the stove are connected with 45 the chimney 9 which is at one end thereof. Adjacent this chimney there is the damper 10 which is operated by means of the handle 11, said damper permitting the smoke to pass directly to the chimney whenever it is 50 not desired to heat the oven. When the damper 10 is closed, the smoke must pass down the flue 12 at the left of Fig. 1.

Surrounding and forming the oven, is a casing 11' which casing produces a flue 12

55 at one end of the stove, and a flue 13 at the bottom of the oven, which later is connected with two flues 14, 15 which extend up at the side of the oven adjacent the fire box and then pass over the top of the oven at front and rear respectively. Both flues 14 and 15 finally lead directly into the chimney 9 and they are both spaced below the stove top. When the damper 10 is raised the smoke will have direct access to the chimney 60 65 9 through the opening covered by said damper so that the smoke will then pass down the flue 12 at the left of Fig. 1 under the stove through the flue 13 and then back over the top through the flues 14 and 15.

From the foregoing construction, it will 70 be seen that when the damper 10 is raised, that the heat from the fire will pass over the top of the oven down at the left of the oven, Fig. 1 underneath the oven, and around the 75 opposite end of the oven and over the top, going into the two separate flues 14 and 15, thereby affording a better distribution of the heating than is possible where a single wider flue is used, as well as affording a greater area of flue surface for heat transfer 80 to the oven.

What I claim is as follows, but various modifications may be made in the construction shown in the drawings and above particularly described form, within the purview 85 of my invention.

A stove having a fire box, an oven formed therein, partitions in the stove forming a central flue with its bottom formed by the top of the oven and extending entirely 90 across one end of the oven and across the bottom of the oven, two other flues connecting the bottom flue with the chimney and extending across one end of the oven adjacent the fire box and over the top of the 95 oven from front to rear and communicating directly with the chimney, one of said flues on each side of the central flue, the top of the stove being spaced away from the two latter flues sufficiently to allow the heat 100 from the fire box to pass over the top of the oven and flues, across the entire width of the stove, and a damper to permit the smoke to pass directly to the chimney after passing through the central flue.

In testimony whereof I have hereunto set my hand this 11th day of July, A. D. 1919.

HENRY PODOLSKY.
